UNITED STATES PATENT OFFICE

164,654

COMBINED MAILING BOX AND LETTER ENVELOPE

Harry Steinberg, New York, N. Y.

Application April 9, 1951, Serial No. 14,756

Term of patent 3½ years

(Cl. D59—8)

To all whom it may concern:

Be it known that I, Harry Steinberg, a citizen of the United States of America, residing in New York city, county of New York, and State of New York, have invented a new, original, and ornamental Design for a Combined Mailing Box and Letter Envelope, of which the following is a specification, reference being had to the accompanying drawing, forming part thereof, wherein:

Figure 1 is a front perspective view of a combined mailing box and letter envelope, showing my new design in an unsealed opened position.

The characteristic features of my design reside in the portions shown in full lines in the drawing.

I claim:

The ornamental design for a combined mailing box and letter envelope, substantially as shown and described.

HARRY STEINBERG.
